His Attorney.

UNITED STATES PATENT OFFICE.

HENRY STANLEY HOLBROOK, OF RUGBY, ENGLAND, ASSIGNOR TO GENERAL ELECTRIC COMPANY, A CORPORATION OF NEW YORK.

ELECTRIC TRANSFORMER.

Application filed March 30, 1926, Serial No. 98,579, and in Great Britain July 7, 1925.

My invention relates to electric transformers and more particularly to spacing members adapted to be inserted between transformer disk coils as disclosed in United States Patent No. 1,549,525, issued August 11, 1925, on an application filed by W. H. Cooney. In this patent, spacing members are described which are so designed as to allow an insulating fluid to pass through transverse ducts in the members and come in contact with as large a surface of the coils as possible, but the portions of a spacing member which are in contact with the transformer coils are slotted inwardly from their edges. The general object of the present invention is to provide a transformer disk coil spacer having transverse ducts arranged to allow an insulating fluid to come in contact with the surfaces of the coils separated by the spacer, the portion of the spacer in contact with the coil surfaces, however, having unbroken edges so that the span of the unsupported portion of a coil between spacers is reduced and greater support is provided for the coils against the mechanical stresses of a short circuit.

The invention will be better understood from the following description, taken in connection with the accompanying drawing, in which Fig. 1 is a sectional plan view of a transformer having coil spacing members constructed in accordance with the invention; Fig. 2 is an exploded view in perspective of one of the spacing members shown in Fig. 1; Fig. 3 is a plan view of a spacing member with its parts assembled, and Fig. 4 is a section on the line 4—4 of Fig. 3.

The particular form of spacing member illustrated in the drawing is made up of a number of layers of suitable insulating material. In the example shown, the spacer consists of four layers, the outer two layers 10 and 11 having a number of openings 12 between their side edges so that these side edges are unbroken and the intermediate or inside layers 13 and 14 having notches 15 extending inwardly from both side edges. Each of the layers comprising the spacer may have a notch 16 in its end to engage a locking strip so that the spacers may be

held in place when assembled in a transformer. In the assembled spacer, the openings 12 and the notches 15 overlap to form transverse passageways so that oil or other insulating fluid may enter the notches 15 at 55 one side of the inside layers 13 and 14, thence pass through the openings 12 in the outside layers 10 and 11 and in contact with the coils which are separated by the spacer and then out through the notches 15 in the 60 other side of the inside layers 13 and 14.

As shown in Fig. 1, the spacers may be arranged radially with respect to the transformer coils and at approximately right angles with the coil conductors. As the side 65 edges of the outer layers 10 and 11 have no notches and are unbroken by the passageways, the unsupported span of coil is nowhere greater than the distance between the adjacent edges of adjacent spacers. 70

In the spacer which has been shown and described, the transverse passageways are at right angles to the sides of the spacer, but it is obvious that the direction of the passageways is not limited to this angle. 75

What I claim as new and desire to secure by Letters Patent of the United States, is,

1. A transformer coil spacer comprising outer layers having openings between their side edges, and inner layers having their edges provided with notches, said openings and notches overlapping and communicating to form transverse passageways for insulating fluid, whereby the side edges of said outer layers are unbroken by said passageways. 80

2. A transformer coil spacer comprising a layer having a notch in each side edge, and a layer having an opening between its side edges, said notches and opening overlapping and communicating to form a transverse passageway for insulating fluid, and the layer with said opening forming an outer face adapted to support a transformer coil, whereby the edges of said coil contacting face are unbroken by said passageway. 95

In witness whereof, I have hereunto set my hand this tenth day of March, 1926.

H. S. HOLBROOK.
